UNITED STATES PATENT OFFICE.

ALLYN RANFT COOPER, OF MARSHALLTOWN, IOWA.

DASH CONTROL.

Application filed March 24, 1924. Serial No. 701,263.

This invention relates to a control device adapted primarily to be located at a distance from the instrument or apparatus which it is to control, although it may be located close 5 or even attached direct to the device. In the form shown herewith it is adapted particularly for the remote control of devices mounted on an automobile, and it may be used as a cut-out control device, to operate 10 a radiator shutter, or to control many other accessory devices which are commonly mounted upon automobiles. It has for one object to provide a control device which is capable of an almost infinite number of adjustment positions, and which may be readily 15 locked in any one of such positions and which may be moved directly to any one of such other positions when unlocked. Other objects will appear from time to time throughout 20 the specification and claims.

My invention is illustrated more or less diagrammatically in the accompanying drawings, wherein:

Figure 1 is a longitudinal cross section 25 with some parts in elevation showing the control device in the locked position.

Figure 2 is a similar view to Figure 1 showing the control device in the unlocked position;

Figure 3 is a transverse cross section taken 30 on the line 3—3 of Figure 1.

Like parts are designated by like characters throughout.

A is a portion of the instrument board of 35 an automobile in which the control device is mounted.

B is a plate to which the control device housing C is secured. B¹ is another plate 40 on the opposite side of the instrument board. By means of bolts B² B² the control device is removably secured in the instrument board.

The housing C as shown is preferably provided with a curved side C¹, and it is provided also with perforated closed ends.

45 Carried within the housing C is the control shaft D. It may be reduced at one end as at D¹ and provided with a perforation D² in which a wire or rod D³ is mounted. This wire extends to the device which is to be controlled, which is not here shown as it forms no part of the present invention. At the other end of the shaft D is a control handle D⁴ by means of which it may be rotated and moved in and out for adjustment. In the 50 form here shown there is provided intermediate the ends of the shaft D, a laterally ex-

tending projection E. As shown this projection is integral with the shaft and forms in reality a laterally bent part of it. While this is a preferable construction, my invention is not limited to it, and this projection might be made in any other form. It need not be integral with the shaft and might take the form of a member partially surrounding the shaft, or otherwise mounted on 65 or secured to it.

As here shown the portion of the housing against which the laterally projecting portion of the shaft bears in the locked position is curved, and the shaft is mounted eccentrically to the curvature. This is a preferable construction but is not essential. This curve might be on the arc of a circle or it might not. This portion need not actually be curved. The projection portion of the 70 shaft can bear against a plane surface or a flat portion sufficiently to take a locking contact without interfering with the construction shown herewith.

As shown there is preferably some play 80 between the parts, and the housing is to some extent elastic or expansible. When the shaft is rotated so that the laterally bent portion comes in locking contact with the housing which encloses it, this housing is to some extent sprung. This is preferable but not essential. The housing might be entirely rigid.

Although I have shown an operative device, still it will be obvious that many 90 changes in size, shape and arrangement of parts might be made without departing materially from the spirit of my invention; and I wish, therefore, that my showing be taken as in a sense diagrammatic.

The use and operation of my invention are as follows:

The control device is mounted to some portion of an automobile, preferably it is mounted as shown on the instrument board. 100 By means of a wire or other connection some device such, for example, as a radiator shutter is operatively connected to the shaft of the control device, and the shutter is caused to move by reciprocation of the shaft. In 105 order to lock the shaft in position and thus hold the device which it controls against movement, the shaft is rotated by means of the handle so that the lateral projection from the shaft comes into locking contact 110 with a portion of the housing. When the shaft is rotated, this lateral projection is

wedged against a portion of the housing thus locked against movement, and in this position the shaft will not rotate of itself nor will it be moved longitudinally, and it 5 and the device which it controls are locked against movement.

When it is desired to move the shutter, for example, the control shaft is rotated and the laterally bent portion upon it is moved out 10 of wedging and locking contact with its housing. The shaft is then moved longitudinally and the device which it controls is thus moved.

By means of this construction the shaft 15 may be positively locked at any point within the limit of the length of the housing which encloses it, and an almost infinite degree of variation of adjustment is thus permitted.

I claim:

20 1. In a control device, a shaft mounted for axial and for rotary movement, a lateral projection from said shaft, a housing for said shaft provided with a curved portion, the shaft being mounted eccentrically with 25 respect to said curved portion, the projection from said shaft adapted to move against the curved portion of the housing to engage the same to lock the parts against movement.

20 2. In a control device, a shaft mounted for axial and for rotary movement, a lateral rigid projection from said shaft intermediate its ends and provided with a curved portion, the projection from the shaft normally 35 out of contact with the curved portion and adapted to be moved against the curved portion of the housing to engage the same and lock the parts against movement.

20 3. In a control device, a shaft mounted for axial and for rotary movement, a lateral projection from said shaft, a housing enclosing said shaft, provided with a curved portion the shaft being mounted eccentrically within said housing, the projection

from the shaft normally out of contact with the curved portion and adapted when the 45 shaft is rotated to engage the curved portion of the housing and to lock the parts against movement.

4. In a control device, a shaft, an operating handle on the same, and a connection 50 portion, a lateral projection from said shaft, a housing enclosing said shaft provided with a curved portion, the shaft being mounted eccentrically within said housing for rotation, the projection from the shaft normally 55 out of contact with the curved portion and adapted to be moved against the curved portion of the housing and to be forced thereagainst with a wedging and locking movement and when so wedged to hold the shaft 60 against movement with respect to its housing.

5. In a control device a shaft mounted for axial and rotary movement, a lateral projection on said shaft intermediate its ends, and 65 an open sided housing partially enclosing said shaft, said projection being normally out of contact with said housing said shaft adapted to be rotated to bring said projection into locking engagement with said housing.

6. In a control device a shaft mounted for axial and rotary movement, a lateral projection on said shaft intermediate its ends, and 75 an open sided housing partially surrounding said shaft and provided with a curved portion the projection from the shaft adapted to be moved against the curved portion of the housing and to be forced thereagainst with a wedging or locking action to hold the 80 parts against movement.

Signed at Marshalltown, county of Marshall and State of Iowa, this 21st day of March, 1924.

ALLYN RANFT COOPER.
